UNITED STATES PATENT OFFICE

2,254,273

GARMENT STRETCHING AND DRYING
FRAME

Jane Van Cleve Dimelow, New York, N. Y.

Application January 6, 1940, Serial No. 312,641

3 Claims. (Cl. 223—69)

My invention relates to improvements in means for stretching and drying garments and the same has for its object to provide a simple, efficient and inexpensive device upon which corsets, girdles and similar garments may be disposed after washing in order to dry and shape the same.

Further, said invention has for its object to provide a device of the character specified which may be readily adjusted, within certain limits, to accommodate garments of different sizes.

Further, said invention has for its object to provide a device of the character specified which includes a pair of correspondingly-shaped frame members whose joint outline or contour corresponds to the shape of the garment to be treated.

Further, said invention has for its object to provide a device of the character specified which includes a pair of similarly-shaped frame members which are movable relative to each other and capable of adjustment in order to increase or vary either the waist measurement or the hip measurement separately, or to vary or change both the hip and waist measurements in accordance with the size of the garment to be stretched and dried.

Further, said invention has for its object to provide a device of the character specified which includes two similarly-shaped frame members which are so connected at their upper and lower ends that the frame members may be adjusted or partially rotated, either at their upper or lower ends, in the arc of a circle having its pivotal point at the opposite ends of said frame members, and then be severally secured to adjusted positions.

Other objects will in part be obvious and in part be pointed out hereinafter.

To the attainment of the aforesaid objects and ends my invention consists in the novel features of construction, and in the combination, connection and arrangement of parts herein-after more fully described and then pointed out in the claims.

In the accompanying drawing—

Figure 1 is a face view showing one form of stretching and drying frame constructed according to and embodying my said invention; the parts being shown in full lines in normal or retracted position, and in broken lines in uniformly extended position;

Fig. 2 is an enlarged detail face view showing the lower corresponding ends of the frame mem-

bers, and the means for connecting and securing the same to adjusted positions;

Fig. 3 is an enlarged horizontal section on the line 3—3 of Fig. 2;

Fig. 4 is a face view showing the frame members spread apart at their upper ends to provide for an increased waist measurement only, and

Fig. 5 is a face view similar to Fig. 4, showing only the lower ends of the frame members spread apart to provide for an increased hip measurement.

In said drawing 10 designates the device comprising a pair of flat, similarly-shaped open work frame members 11, 11^a having straight registering, vertical inner edges 12, 12^a, and reversely-curved outer edges 13, 13^a which correspond in general to the waist and hip contours of the female figure. The said frame members are preferably made of laminated wood and painted or otherwise suitably treated to render the same impervious to moisture.

15, 15^a denote flat, longitudinal link members uniting the frame members 11, 11^a at their upper and lower ends. The said link members are preferably formed of metal, and each comprises a solid portion 16, and a longitudinally-slotted portion 16^a extending therefrom. The solid portion 16 is pivotally fixed adjacent the inner end of its slotted portion 16^a to the frame member 11 by a bolt 18 and nut 19, and adjacent the end of its solid portion said link is provided with a short, curved slot 20 arranged transversely of the link member through which extends a bolt 21 secured in the frame member 11. The bolt 21 is provided with a wing nut 22, and the cooperating frame member 11^a is provided with a similar bolt 21^a which passes through the slotted portion 16^a of the link member 15 and is provided with a wing nut 22^a. The said bolts 21 and 21^a serve to maintain the lower ends of the frame members 11, 11^a adjustably secured together.

The upper ends of the frame members 11, 11^a are secured together by a link construction similar to that above described, except that the positions of the parts are reversed, i. e. the solid portion 16^a of the link 15 is pivotally fixed to the frame member 11^a, and the slotted portion 16^a is adjustably secured to the frame member 11.

To facilitate the spreading apart of the upper ends of the frame members relative to the lower ends thereof, or vice versa, the said frame members have their inner contiguous upper and lower corners rounded at 24 to permit of a limited

circular movement of the frame members without causing any undue binding or straining of the parts.

The upper, outer corner of each frame member 11, 11^a is provided with an aperture in which is disposed a ring 25, to facilitate the hanging of the frame with the garment thereon.

The operation of my device will be largely obvious from the foregoing description. It should be noted, however, that an important feature of the construction of the frame is that it permits of the movement of the two frame members with their inner, vertical edges in parallelism, and it also permits either the upper or lower ends of the frame members to be spread apart radially relative to the opposite ends in order to adapt the frame to garments having a proportionately larger waist measurement or a proportionately larger hip measurement without disturbing the adjustment of the other ends of the frame members.

Having thus described my said invention what I claim and desire to secure by Letters Patent is:

1. A device of the character described comprising a pair of closely-associated flat frame members having straight, registering inner edges and reversely-curved outer edges, and means arranged wholly within the outlines of said frame members for maintaining said frame members operatively associated; said means including flat link members arranged adjacent the upper and lower edges of said associated frame members; each of said link members including a solid intermediate portion and slotted end portions extending therefrom, one of said link members being pivotally secured at its intermediate portion to one of said frame members with one of its slotted end portions extending over the other of said frame members, and the other of said link members having its intermediate portion pivotally secured to said last-named frame member and one of its slotted ends extending over said first-named frame member to permit of either end of either frame member to be partially rotated about the pivotal connection at the other end thereof whereby to vary the transverse dimension of the device at either end without change of dimension at the other end, and clamping screws on each of said frame members severally engaging with the slotted ends of said link members for securing the same in position and said frame members in adjusted relation.

2. A device of the character described comprising a pair of closely-associated flat frame members having conforming vertical inner edges and reversely-curved outer edges corresponding generally to the contour of the waist and hips of the female figure, and means arranged wholly within the outline of said frame members for maintaining said frame members in parallelism and operatively associated; said means including flat link members arranged adjacent the upper and lower edges of said associated frame members; said link members each including a solid intermediate portion, a longitudinally-slotted end portion, and a transversely-slotted end portion, and one of said link members having its intermediate portion pivotally fixed to its respective frame member and its longitudinally-slotted end portion extending over the other of said frame members, and the other of said link members having its intermediate portion secured to said last-named frame member and its longitudinally slotted end portion extending over said first-named frame member to permit of either end of said frame members to be partially rotated about the pivotal connection at the other end thereof whereby to vary the transverse dimension of the device at either end without change of dimension at the other end, and clamping screws fixed in said frames and severally engaging the slotted end portions of said link members for permitting the adjustment of either pair of frame ends independently of the other pair of frame ends.

3. A device of the character described comprising a pair of closely-associated correspondingly-shaped frame members having conforming adjacent edges and reversely-curved opposite edges, and connecting means for securing said frame members in adjusted relation, said connecting means each including a link member pivotally secured intermediate its ends to one end of one of said frame members by a pivot having fixed position on said frame member, said link member having rotary movement only on said pivot and having one of its ends extending over the other of said frame members, and means on said frame members severally engaging the opposite ends of said link members for securing said frame members to adjusted position.

50 JANE VAN CLEVE DIMELOW.
